Atty

UNITED STATES PATENT OFFICE.

EWALD A. BARTEIT, OF NEW HAVEN, CONNECTICUT, ASSIGNOR TO THE GEOMETRIC TOOL CO., OF NEW HAVEN, CONNECTICUT, A CORPORATION.

DIE HEAD.

Application filed May 8, 1926. Serial No. 107,645.

Fig. 1. A view mainly in side elevation and partly in longitudinal section of a die-head embodying my invention.

Fig. 2. A plan view thereof with part of 5 the operating-sleeve broken away.

Fig. 3. A view thereof mainly in front elevation and partly in vertical section.

Fig. 4. A detached view in front elevation of one of the spring-actuated retracting-10 plungers.

Fig. 5. An end view thereof.

Fig. 6. A detached view in side elevation of one of the chasers.

My invention relates to an improvement 15 in die-heads of that class having radially-movable chasers forced inwardly into their cutting positions by means of an operating-member which has chaser-operating, chaser-retracted, and chaser-clearance positions, the 20 object being to produce a simple, convenient and effective tool constructed with particular reference to yieldingly holding the chasers in the tool when the said operating-member is moved into its chaser-clearance position, in 25 which the chasers are inserted into and removed from the fixture.

With these ends in view, my invention 30 consists in a die-head having chasers, an operating-member therefor, and means for yieldingly retaining the chasers in the die-head when the said operating-member is moved into its chaser-clearance position.

My invention further consists in a die-head characterized as above and having frictional means for yieldingly retaining the 35 chasers in the die-head when the said operating-member is moved into its chaser-clearance position.

My invention further consists in a die-head having certain details of construction 40 and combinations of parts as will be herein-after described and particularly recited in the claims.

In carrying out my invention, as herein 45 shown, it is embodied in a die-head of standard construction having a skeleton-body 10 provided with a shank 11 by means of which it is mounted for use. The said body mounts a chaser-operating member in the form of a 50 sliding operating-sleeve 12 adjusted in its position for varying the cutting diameter of the die-head by means of an ordinary adjusting-nut 13, the said sleeve having a forward or operating position, an intermediate or

chaser-retracted position, and a rear or 55 chaser-clearance position.

The said body 10 is provided in its forward face with four equidistant radial slots 14 respectively receiving four chasers 15 having cutting-teeth 16 at their inner ends, and 60 bevels 17 at their outer ends co-acting with cam-surfaces 18 formed by notching the inner edge of the forward end of the sleeve 12. For the retraction of the several chasers 15, each is provided with a rearwardly-projecting pin 19. These pins enter notches 20 respectively formed in the outer ends of each of four radially-movable plungers 21 located in as many cylindrical chambers 22 formed in the die-body 10 at points directly back of 70 the chaser-slots 14 aforesaid, the said chambers and slots being connected by passages 23 through which the pins 19 project into the chambers 22, in which the plungers are located, as aforesaid. The said plungers are 75 provided with bores 24 entering them from their inner ends for the reception of chaser-retracting springs 25 by which the plungers and hence the chasers are radially retracted 80 into their retired positions when the operating-sleeve 12 is moved rearwardly into its intermediate and chaser-clearance positions.

To limit the outward movement of the plungers 21 under the influence of the springs 25, stop-screws 26 are mounted in 85 the die-body 10 in position to be engaged by the outer ends of the plungers when they have been pushed to the outward limit of their radial movement by the said springs 25.

Normally, the chasers 15 are held in the 90 radial slots 14 by the direct engagement of their outer ends by the sleeve 12 when the same is in its operating and intermediate positions, as shown by full lines and by broken lines 27 respectively in Fig. 1.

To prevent the chasers 15 from falling out of the slots 14 when the sleeve is moved into its fully-retired or chaser-clearance position, as shown by broken lines 28 in Fig. 1, their pins 19 are frictionally, and therefore 100 yieldingly, gripped between the pairs of fingers 29 formed by the production of the notches 20 in the outer ends of the plungers for the reception of the pins. To secure added resiliency, the plungers are formed 105 with longitudinal slots 30 which permit one of each pair of the said fingers to be set inwardly for the resilient holding of the pins

which their notches 20 receive, the plungers themselves being held in the die-head by the stop-screws 26 aforesaid and in turn yieldingly gripping the pins 19 of the chasers to prevent the same from falling out of the tool by gravity or vibration, when the sleeve 12 thereof is moved into its chaser-clearance position, as shown by the broken lines 28. This yielding coupling of the chasers in the manner described with the plungers does not interfere with the easy manual withdrawal 10 of the chasers from the tool when required. On the other hand, it facilitates the assembling of the chasers in the tool by enabling them to be individually snapped into place, 15 as it were, without the necessity of manually holding them in place until all have been positioned, and the sleeve has been moved into engagement with their outer ends.

I would have it understood that the term 20 "spring-pressed," as used herein, is intended by me to cover a member which is in itself resilient, as, for instance, one of the two fingers 29 of the respective plungers, or any other member intrinsically resilient or a non-resilient member acted upon by a separate 25 spring.

Furthermore, in referring to a member as 30 "engaging with a chaser," I wish to be understood as including within the scope of such term a member directly engaging with the chaser or indirectly through the medium of a part carried thereby.

I claim:

35 1. A die-head having chasers, an operating-member for operating them and holding them in place, spring-actuated plungers each having a resilient finger, and pins connecting the chasers and plungers and engaged 40 by the finger of the latter for yieldingly retaining the chasers in the die-head when the operating-member thereof is in its chaser-clearance position.

2. A die-head having radially-movable 45 and radially-removable chasers, a chaser operating sleeve having chaser-closing, chaser-retracted, and chaser-clearance positions, radially-movable spring-actuated plungers

located in the die-head, pins carried by the said chasers and engaged by said plungers, 50 and spring-pressed means yieldingly connecting the chasers and plungers through the said pins, whereby the chasers are yieldingly held in the die-head against radial withdrawal therefrom when the said sleeve 55 is moved into its chaser-clearance position.

3. A die-head having radially-movable chasers, a chaser operating sleeve having chaser-closing, chaser-retracted and chaser-clearance positions, pins carried by the respective chasers, radially-movable spring-actuated plungers located in the die-head, notched for the reception of the said pins and slit for the production of fingers set to frictionally engage the said pins for yieldingly coupling the chasers with the plungers for yieldingly holding the chasers in the die-head when the sleeve is moved into its chaser-clearance position.

4. A die-head having radially-movable 70 and radially-removable chasers, a chaser-operating member having chaser-closing, chaser-retracted and chaser-clearance positions, and means for yieldingly retaining the chasers in the die-head against radial withdrawal therefrom when not positively held therein by the said chaser-operating member, said means including a spring-pressed member engaging the respective 75 chasers.

5. A die-head having radially-movable and radially-removable chasers, a chaser-operating sleeve having chaser-closing, chaser-retracted and chaser-clearance positions, radially-movable spring-actuated 85 plungers for the retraction of the chasers, means for limiting the radial outward movement of the plungers, and means for yieldingly coupling the chasers with the plungers to prevent the radial withdrawal of the 90 chasers from the die-head when not positively held therein by the said sleeve.

In testimony whereof, have signed this specification.

EWALD A. BARTEIT.
